UNITED STATES PATENT OFFICE.

MARTIN ELZAS, OF LOS ANGELES, CALIFORNIA, ASSIGNOR TO ELKO B. DYKXHUIZEN AND ROBERT F. LANGER, BOTH OF LOS ANGELES, CALIFORNIA.

BUTTER-DISH REFRIGERATOR.

1,150,583.

Specification of Letters Patent. Patented Aug. 17, 1915.

Application filed June 15, 1914. Serial No. 845,201.

To all whom it may concern:

Be it known that I, MARTIN ELZAS, a subject of the King of Great Britain, residing at Los Angeles, in the county of Los Angeles and State of California, have invented certain new and useful Improvements in Butter-Dish Refrigerators, of which the following is a specification.

My invention relates to improvements in refrigerators, adapted to be placed upon a butter dish or plate, for maintaining the butter suitably cool, during use upon the table or the like.

An important object of the invention is to provide a device of the above mentioned character, which is simple in construction, inexpensive to manufacture, and highly convenient in use.

Other objects and advantages of the invention will be apparent during the course of the following description.

In the accompanying drawings forming a part of this specification and in which like numerals are employed to designate like parts throughout the same, Figure 1 is a central vertical sectional view through a device embodying my invention, and Fig. 2 is a plan view of the same, with parts removed.

In the drawings wherein for the purpose of illustration is shown a preferred embodiment of my invention, the numeral 5 designates a receptacle as a whole, comprising preferably annular spaced inner and outer walls 6 and 7, providing a water receiving chamber or jacket 8, the lower end of which is permanently closed, as shown. The receptacle 5 has the lower end of its opening or bore open, as shown at 9. Arranged within the upper portion of the opening or bore 9 is an ice holding compartment 10, which is preferably secured to the inner wall 6. This ice holding compartment is tapered and decreases in diameter downwardly. The ice holding compartment 10 has communication with the chamber 8 by means of a pipe 11.

The numeral 12 designates a cover, carrying annular depending flanges 13 and 14, adapted to snugly engage with the walls 6 and 7 respectively. The cover 12 has a han-

dle 15, by means of which the entire device 50 is raised and lowered, in use, the flanges 13 and 14 having sufficient frictional engagement with the walls 6 and 7 to hold these parts together during the manipulation of the entire device by the handle 15. While it 55 is preferred to secure the cover 12 to the receptacle 5 by means of the flanges, it is obvious that other means could be employed.

In use, the device is placed upon the butter dish or plate, and the butter projects up into 60 the lower end of the opening or bore 9. The ice within the compartment 10 serves to keep the butter suitably cool, and the cold water from the butter descends through pipe 11 and enters the chamber 8, which also aids in 65 cooling the butter.

It is to be understood that the form of my invention herewith shown and described is to be taken as a preferred example of the same, and that various changes in the shape, 70 size, and arrangement of parts may be resorted to without departing from the spirit of the invention or the scope of the subjoined claim.

Having thus described my invention, I 75 claim:

A refrigerator adapted to be arranged upon a butter dish or plate; comprising a receptacle including spaced inner and outer walls providing a water receiving chamber 80 or jacket; an ice holding compartment arranged within the upper portion of the receptacle and secured to the inner wall of the receptacle; a pipe establishing communication between the interior of the ice holding 85 compartment and the water receiving chamber or jacket; and a cover provided with a handle, said cover being detachably secured to the receptacle and adapted to raise and lower said receptacle and closing the upper 90 ends of the ice holding compartment and the water receiving chamber or jacket.

In testimony whereof I affix my signature in presence of two witnesses.

MARTIN ELZAS.
